US0D1081152S

(12) **United States Design Patent** (10) **Patent No.:** **US D1,081,152 S**
(45) **Date of Patent:** **** Jul. 1, 2025**

(54) **BRUSH HEAD**

- (71) Applicant: **Colgate-Palmolive Company**, New York, NY (US)
- (72) Inventor: **Geoffrey Baldwin**, Westport, CT (US)
- (73) Assignee: **Colgate-Palmolive Company**, New York, NY (US)
- (**) Term: **15 Years**
- (21) Appl. No.: **29/934,632**
- (22) Filed: **Mar. 27, 2024**

Related U.S. Application Data

- (62) Division of application No. 29/819,826, filed on Dec. 17, 2021, now Pat. No. Des. 1,024,567.

(57) **CLAIM**

The ornamental design for a brush head, as shown and described.

DESCRIPTION

FIG. 1 is a front perspective view of a brush head showing my new design according to a first embodiment;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front perspective view of a brush head showing my new design according to a second embodiment;
FIG. 10 is a rear perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof; and,
FIG. 16 is a bottom view thereof.

The broken lines illustrate portions of the brush head that form no part of the claimed design. The grayscale represents a contrast in appearance.

1 Claim, 10 Drawing Sheets
